(57) **CLAIM**

The ornamental design for a game tile, as shown and described.

DESCRIPTION

This invention was made with Government support under Award No. 1346821 awarded by the Small Business Innovation Research (SBIR) Program of the National Science Foundation (NSF). The Government has certain rights in the invention.

FIG. 1 is an isometric view of a game tile showing our new design;

FIG. 2 is a top view of the game tile of FIG. 1;

FIG. 3 is a front view of the game tile of FIG. 1;

FIG. 4 is an isometric view of a game tile according to another embodiment of our new design;

FIG. 5 is a top view of the game tile of FIG. 4; and,

FIG. 6 is a front view of the game tile of FIG. 4.

The broken lines show portions of the game tile which form no part of the claimed design.
